UNITED STATES PATENT OFFICE.

PHILIP CASTELLANO AND JOSEPH AUGELLO, OF NEW YORK, N. Y.

ROAD-MAKING MACHINE.

Application filed February 28, 1928. Serial No. 257,557.

Our invention relates to road making machines and refers particularly to machines adapted for the laying of asphalt and similar plastic road making materials.

5 In the laying of asphalt and similar plastic materials it is essential that layers of uniform thickness be produced and it is further essential that means be employed whereby the thickness of such layers may be controlled.

The present usually employed method is to dump a large quantity of asphalt in one place and then carry it to different portions of the road bed and by means of hand rakes 15 form it into a smooth surface.

This method is uneconomical, unscientific and uncertain in results.

The repeated handling of the heated asphalt frequently cools it to a consistency 20 which is difficult or impossible to work. It requires a large number of workmen to carry the asphalt to the desired portions of road bed. It requires a large number of men to rake it into a smooth surface. The formation 25 of a uniform thickness is dependent upon the opinion of the workmen. The production of the desired thickness is obtained only by repeated and constant tests of depth. Any inequality of thickness requires an additional amount of working and raking of the rapidly 30 cooling asphalt.

All of the above and many other objectionable features of the present employed methods are avoided and overcome by the device 35 of our invention.

By the movement of our device there is continuously deposited upon a road bed, an asphalt layer of any desired thickness which is automatically smoothed and leveled, the 40 amount of asphalt deposited being controlled by our device and its uniformity of thickness being accurately governed and insured by the scraping, or raking, device which is an element of our device.

45 As the asphalt is deposited from the conveying truck directly upon the road bed in the form of the desired layer, no carrying or shovelling is necessary.

It is evident, therefore, that by means of 50 our device it is possible to accurately deposit a predetermined thickness of asphalt economically, efficiently and rapidly.

The advantages of our device will be evident upon a consideration of our specification 55 and its accompanying drawings.

In the accompanying drawings illustrating

one form of the device of our invention similar parts are designated by similar numerals.

Figure 1 represents a broken top view of one form of the device of our invention. 60

Figure 2 is a side view of the device of Figure 1 partly broken away for purposes of clearness of description.

Figure 3 is an end view of the device of Figure 1. 65

Figure 4 is a broken top view of the scraping elements of our device.

Figure 5 is a section through the line 5—5 of Figure 2.

Figure 6 is a top view of the guiding elements of our device. 70

Figure 7 is an enlarged vertical section of the pocket changing elements of our device.

The particular form of the device of our invention illustrated in the accompanying 75 drawings comprises an asphalt receptacle having the sides 10 and 11, the front 12, the back 13 and the downwardly inclined bottom 14, the latter having a longitudinal opening 15 at the lower portion thereof. A hood 16 80 extends around the upper portion of the rear of the receptacle. The receptacle is mounted upon the two traction wheels 17, 17.

The revoluble shaft 18, to which are fixedly attached the two wheels 17, 17, passes through 85 the lower portion of the receptacle, that portion of the shaft 19 within the receptacle being of rectangular formation.

Fixedly attached to the rectangular shaft 19 are angle arms 20, 20. 90

Two shafts 21, 22 pass through the receptacle, the inner portions 23, 24 of said shafts being rectangular, the shaft 23 carrying the mixing blades 25, 25, and the shaft 24 carrying the mixing blades 26, 26. 95

Exterior of the side 10, the shaft 22 carries the fixedly attached sprocket 27, the shaft 21 carries the fixedly attached sprocket 28 and the shaft 18 carries the fixedly attached sprocket 29. The side 10 also carries the 100 sprocket idler 30.

A link chain 31 passes over the sprockets 27, 28, 29 and 30, so that a forward movement of the receptacle will cause the series of mixing blades 25, 25 and 26, 26 to move inwardly 105 with respect to each other and downwardly with respect to the receptacle.

Carried by each side of the back 13 is an angular support, one arm of which 32 is fixedly attached to the lower portion of the 110 back 13 and the other arm 33 is attached to the bottom 14. This support has the rear-

wardly extended member 34 having a vertical slot 35 therein.

A revoluble shaft 36 extends through and is revoluble within the two supporting arms 5 32, 32.

Fixedly attached to the shaft 36 is a raising arm 37, the lower portion of which 38 is inclined rearwardly and downwardly and has a longitudinal slot 39. The upper portion 10 of the arm 37 carries a spring catch 40, the tooth of which is capable of placement in a series of recesses 41, 42, 43 and 44 in the segmental arm 45 which is attached to the back 13. Fixedly attached to the shaft 36 is 15 a counterweight 46.

Carried by the members 34, 34, and passing through the slots 35, 35, is a leveling or scraping device 47, one end of which 48 is cylindrical and passes through the opening 39 of 20 the arm member 38.

A cross-bar 49, having the annular member 50 is fixedly attached to the forward portion of the receptacle by the supports 51, 51, 52, 52. Pivotaly attached to the annular member 50 is an annular member 53 carrying the shaft 54 upon which the two traction wheels 55, 55 are revoluble. The annular member 53 also carries the eye-bar 56 pivotaly attached at 57.

30 The operation of my device is as follows:—

The eye-bar 56 is attached to the rear of a truck receptacle carrying a large quantity of soft asphalt and is so inclined that the contents therein flow gradually into the device.

35 The truck is then moved forwardly dragging the device after it. The movement of the traction wheels 17, 17, revolves the mixing blades 25, 25, 26, 26, thus mixing the asphalt falling thereon and passing it downwardly 40 upon the revolving members 20, 20, which in turn cause the asphalt to pass outwardly through the longitudinal opening 15.

It will be noted that as the members 20, 20, revolve they form pockets with the bottom 45 14, the contents of which pass through the opening 15, and hence, the amount of asphalt delivered will depend upon the capacity of these pockets.

As it is generally desirable that a certain 50 amount of asphalt be delivered in order to produce a layer of desired thickness, it is advisable that the capacity of these pockets be changeable in order to meet different requirements.

55 This is accomplished by the attachment of channel irons to the members 20, 20, as indicated in Figure 7 as follows:—

Channel irons 58, 58 of the desired shape are introduced through the opening 15 and 60 bolted to the members 20, 20. The shape of the channel irons will therefore control the size of the pockets.

The operation of the leveling device is as follows:—

65 The recesses 41, 42 and 43 are so positioned

as to set the lower edge of the scraper 47 a predetermined distance above the road bed. If for instance it is desired to level an asphalt bed 60 of one inch thickness the catch 40 is placed in recess 41, for a two inch bed it would be placed in recess 42, for a three inch bed in recess 43 a further number of recesses being employed as desired. It will be noted that the scraper 47 is thus placed and locked in any desired position above the road bed 59. 75

When the device reaches an obstruction in the road, such as a man-hole, and it is necessary to raise the scraper 47, the arm 37 is raised, thus raising the scraper vertically along the slot 35, and it may be locked in this raised position, if desired, by inserting the catch 40 in notch 44. 80

It will thus be seen that our device presents a means whereby a continuous layer of asphalt of practically any desired thickness 85 may be laid upon a road bed, the amount of asphalt deposited being determined by the size of the asphalt pockets and the asphalt thus deposited being leveled into the desired thickness of layer. 90

We do not limit ourselves to the particular size, shape, number or arrangement of parts as shown and described as these are given simply as a means for clearly describing the device of our invention. 95

What I claims is:—

1. In a road making machine, in combination, a receptacle having an opening therein, a frame carrying said receptacle, traction wheels carried by said frame, revoluble mixing blades within said receptacle, means whereby the revolution of said traction wheels will cause contents of said receptacle to pass downwardly through said receptacle opening, a supporting arm carried by each lower rear side of said frame having a vertical slot therein, a downwardly extended scraping device slidable within said vertical slots, means for moving said scraping device within said slots and means for retaining said scraping device at a predetermined position within said slots. 100

- a frame carrying said receptacle, traction wheels carried by said frame, revoluble mixing blades within said receptacle, means whereby the revolution of said traction 5 wheels will cause contents of said receptacle to pass downwardly through said receptacle opening, a supporting arm carried by each lower rear side of said frame having a vertical slot therein, a revoluble shaft carried by 10 said supports, a downwardly extended scraping device slideable within said slots, a raising arm fixedly attached to said shaft and connected with said scraping device and means whereby a movement of said raising 15 arm will move said scraping device within said slots.
4. In a road making machine, in combination, a receptacle having an opening therein, a frame carrying said receptacle, traction 20 wheels carried by said frame, revoluble mixing blades within said receptacle, means whereby the revolution of said traction wheels will cause contents of said receptacle to pass downwardly through said receptacle 25 opening, a supporting arm carried by each lower rear side of said frame having a vertical slot therein, a revoluble shaft carried by said supports, a downwardly extended scraping device slideable within said slots and a raising 30 arm fixedly attached to said shaft having an angularly positioned slot therein within which the scraping device is slideable, so positioned that a movement of said arm will cause said scraping device to move within said slots.
5. In a road making machine, in combination, a receptacle having an opening therein, a frame carrying said receptacle, traction 35 wheels carried by said frame, revoluble mixing blades within said receptacle, means whereby the revolution of said traction wheels will cause contents of said receptacle to pass downwardly through said receptacle opening, a supporting arm carried by each lower rear side of said frame having a vertical slot therein, a revoluble shaft carried by said supports, a downwardly extended scraping device slideable within said slots, a raising arm fixedly attached to said shaft having an angularly positioned slot therein within which the scraping device is slideable, so positioned that a movement of said arm will cause said scraping device to move within said slots.
6. In a road making machine, in combination, a receptacle having an opening therein, a frame carrying said receptacle, traction 40 wheels carried by said frame, revoluble mixing blades within said receptacle, means whereby the revolution of said traction wheels will cause contents of said receptacle to pass downwardly through said receptacle opening, a supporting arm carried by each lower rear side of said frame having a vertical slot therein, a revoluble shaft carried by said supports, a downwardly extended scraping device slideable within said slots, a raising arm fixedly attached to said shaft having an angularly positioned slot therein within which the scraping device is slideable, so positioned that a movement of said arm will cause said scraping device to move within said slots.
7. In a road making machine, in combination, a receptacle having an opening therein, a frame carrying said receptacle, traction 45 wheels carried by said frame, revoluble mixing blades within said receptacle, means whereby the revolution of said traction wheels will cause contents of said receptacle to pass downwardly through said receptacle opening, a supporting arm carried by each lower rear side of said frame having a vertical slot therein, a revoluble shaft carried by said supports, a downwardly extended scraping device slideable within said slots, a raising arm fixedly attached to said shaft having an angularly positioned slot therein within which the scraping device is slideable, so positioned that a movement of said arm will cause said scraping device to move within said slots.
8. In a road making machine, in combination, a receptacle having an opening therein, a frame carrying said receptacle, traction 50 wheels carried by said frame, revoluble mixing blades within said receptacle, means whereby the revolution of said traction wheels will cause contents of said receptacle to pass downwardly through said receptacle opening, a supporting arm carried by each lower rear side of said frame having a vertical slot therein, a revoluble shaft carried by said supports, a downwardly extended scraping device slideable within said slots, a raising arm fixedly attached to said shaft having an angularly positioned slot therein within which the scraping device is slideable, so positioned that a movement of said arm will cause said scraping device to move within said slots and means for maintaining said

scraping device at any predetermined position within said slots.

6. In a road making machine, in combination, a receptacle having an opening therein, a frame carrying said receptacle, traction wheels carried by said frame, revoluble mixing blades within said receptacle, means whereby the revolution of said traction wheels will cause contents of said receptacle to pass downwardly through said receptacle opening, a supporting arm carried by each lower rear side of said frame having a vertical slot therein, a revoluble shaft carried by said supports, a downwardly extended scraping device slideable within said slots, a raising arm fixedly attached to said shaft having an angularly positioned slot therein within which the scraping device is slideable, so positioned that a movement of said arm will cause said scraping device to move within said slots, a spring catch carried by said arm a tooth of which is capable of insertion within recesses within a notched sector, and a notched sector.

7. In a road making machine, in combination, a receptacle having an opening therein, a frame carrying said receptacle, traction wheels carried by said frame, revoluble mixing blades within said receptacle, means whereby the revolution of said traction wheels will cause contents of said receptacle to pass downwardly through said receptacle opening, a supporting arm carried by each lower rear side of said frame having a vertical slot therein, a revoluble shaft carried by said supports, a downwardly extended scraping device slideable within said slots, a raising arm fixedly attached to said shaft having an angularly positioned slot therein within which the scraping device is slideable, so positioned that a movement of said arm will cause said scraping device to move within said slots, a spring catch carried by said arm a tooth of which is capable of insertion within recesses within a notched sector, a notched sector and a counter weight for said scraping device fixedly attached to said revoluble shaft.

Signed at New York city, in the county of New York and State of New York, this 27th day of February, 1928.

PHILIP CASTELLANO.
JOSEPH AUGELLO.
